UNITED STATES PATENT OFFICE

2,154,008

COAL RANGE

Ambrose R. Pierce, St. Louis, Mo., assignor to
 American Stove Company, St. Louis, Mo., a corporation of New Jersey

Application November 8, 1937, Serial No. 173,472

3 Claims. (Cl. 126—1)

This invention relates to certain improvements in coal ranges which has in view the following objects.

One object of the present invention is to construct a coal range which is provided with two outwardly swinging outer doors which are made of a size to cover the front end of the range from bottom to top and from side to side, that is to say, there are no separate exposed frame or panels but only two doors. This has several structural advantages, as will be pointed out hereinafter.

Another object of the present invention is that the two-door structure has each door to occupy one half of the front end of the range whereby one half of the interior contains a reservoir and coal compartment, a large utensil compartment, a reservoir compartment above the utensil compartment; it enables said utensil compartment to have its rear wall provided with an ample air supply for the coal compartment and the inner wall of the said utensil compartment provided with an adjustable means for controlling the amount of air fed to the coal compartment, and all of said compartments closed by a single horizontally swinging door. The other half of the structure is provided with a single door like that already described and the upper portion of this other half forms an oven, and below the said oven is a second large utensil compartment and this other half, as stated, is closed by a single door and when the two doors are closed the entire front end of the structure is composed of the two doors.

There are other advantages in this structure of a new coal range, as will appear from the following description.

In the drawings:

Fig. 1 is a perspective view of my improved coal range.

Fig. 2 is a perspective view showing the two doors open and exposing the interior construction of the range.

Fig. 3 is a fragmentary perspective view disclosing the lower end of the utensil compartment which is below the said reservoir and also exposing the outer door for closing the ash tray, the said horizontally swinging doors being omitted in said fragmentary view.

Coal and wood range structures as heretofore known to me are composed of several doors, and panels and other structures which are dispensed with in this improved stove, thus making a structure which costs considerably less than the prior

structures and the whole stove presenting a very simple, novel and attractive structure.

Referring now to the drawings it will be observed that the front of the range comprises two outer doors *a* and *b*. These doors have their outer edges hinged at *c* and *d* to the outer edge of the ends *e* of the range. The two doors *a* and *b* are each in width one half of the front of the range and when these doors are closed the range presents an extremely simple as well as attractive structure. At the upper edge of the range is a narrow frame *f* and at the rear edge of the range is a splash back *g* having at its upper end preferably a shelf *h*. The top of this range is provided at one end with a water reservoir *i* and the top of this reservoir is closed by a suitable pivotal cover *j* which has its rear edge pivoted to the adjacent edge of another part *k* of the cover for said reservoir. The part *k* may be or may not be hinged at its rear edge to the said frame *f* located at the upper end of the range.

Formed adjacent to the said reservoir *i* is the coal compartment *l* which has its outer end provided with a door *m* the lower edge of the door being suitably pivoted to the grate frame—not shown—so that by means of a handle *n* the said door can be swung downward and outward to allow access within the said coal or wood compartment. This compartment as shown in dotted lines in Fig. 2 is provided with suitable grates *o* and below these grates is an ash pit *p* and below this ash pit is a large ash pan *q* having a suitable hinged handle *r* for withdrawing the said ash pan. Below the reservoir *i* is a large utensil compartment *s* which has formed in its back wall a large air opening *t* to supply the compartment with ample air which in turn flows in the grate compartment through passages *u*, which passages are controlled by a suitable damper *v*. Also as shown this compartment *s* has its bottom provided with a plurality of air passages *w*. All of the foregoing constructions occupy one half of the range and all of these compartments are closed by a single door *a*.

The other half of the range inside of the door *b* has its upper portion consisting of an oven *1* and below this oven is a compartment *2*, and preferably between these compartments *1* and *2* is an opening for a clean-out door *3* through which the accumulated soot and ashes can be readily removed. These compartments *1*, *2* and *3* comprise the other half of the range and when the door *b* is closed these compartments are likewise closed, and when both the doors *a* and *b* are closed the

45

50

55

range presents an extremely simple and attractive structure.

The top of the range comprises in addition to the parts *j* and *k* the removable fire box covers **4** which are located immediately above the said coal compartment **1** and also comprises the two removable covers **5** and a removable cooking top plate **6**.

The front side of the range in addition to the doors *a* and *b* is provided with a suitable surrounding frame which consists of the parts **8**, **9**, **10**, **11**, **12** and **13**.

The doors *a* and *b* are provided with any suitable form of handle such for instance as indicated by **14** by means of which the said doors can be opened and closed. It will also be readily understood that the hinges *c* may be of the well known spring type so that they will automatically close.

20 From the above description it will be seen that the reservoir is of large capacity of a width substantially one-fourth the length of the complete range and has a considerable depth, and that access can be had through the cover *j* which makes it easy in dipping water from the said reservoir. It will be seen that the inner wall of the reservoir abuts against the adjoining wall of the coal compartment and that heat is readily conveyed by conduction to the water within the **30** reservoir.

It will also be observed from the foregoing that the strength of the complete structure at its front portion comprises the parts numbered **8** to **12** inclusive and that this part of the range **35** is completely concealed when the doors are closed and that the grates *o* can be removed through the front of the coal compartment and that the coal compartment can be composed of removable linings of any desired material and that either **40** coal or wood can be readily supplied through the front side of the structure by opening the door *m*, or coal can be supplied to the compartment by removing one or more of the cover plates **4**. It will also be readily understood that the covers **45** *j* and *k* for the reservoir can be insulated as may be desired. This construction provides ample utensil compartments as well as ample reservoir, coal compartments and oven, all of which are concealed when the doors are closed leaving only **50** the doors visible from the front of the range.

The door *b* is provided with an inwardly projected insulation portion **16** which is of a size to fit in the open end of the oven **1** and thus form an insulated outer wall for the said open-ended **55** oven.

Also the door *a* is provided with an inwardly projecting portion **17** which fits against and closes the outer ends of the reservoir and utensil

compartments and for the outer end of the fire box. The doors *a* and *b* additionally are insulated and fit against the front frame of the parts **8** to **13** inclusive producing tight insulated doors having the projecting portions that afford the **5** additional insulation for the outer ends of said compartments.

The range may be supported upon any suitable base portion **15** that may be desired.

I desire it to be understood that variations in **10** the constructions described may be made without departing from the scope of the invention.

I claim:

1. A coal range comprising a housing having its top consisting of a reservoir opening at one **15** end, and the balance of said top comprising a cooking top, a reservoir under said opening, a coal compartment adjacent said reservoir and an oven adjacent said coal compartment, said oven having its outer end open, a door hinged at **20** its outer edge to the outer edge of one end of said housing said door extending over and closing said oven, and a second door hinged at its outer edge to the other outer edge of said housing and closing that part of said housing not closed by the **25** first mentioned door, the inner edges of said doors abutting, the said open end of said oven being closed and opened by the first mentioned door.

2. A coal range comprising a housing having **30** at its upper end a cooking top and a reservoir extending only part of the way down leaving a compartment in said housing with an open outer end, a coal compartment in said housing under said cooking top, an oven having its outer end **35** open said oven located at the inner side of said cooking top, two doors hinged at their outer edges to the outer edges of the ends of said housing, one door acting to close and open said open ended oven and the other door acting to open **40** and close said open ended compartment, said doors together acting to also close the outer end of said housing.

3. A coal range comprising a housing having a cooking top and a reservoir, a coal compartment and an oven, said housing having also a compartment beneath said reservoir, said coal compartment having its outer end closed, the inner wall of said compartment having openings **45** communicating with the lower part of said coal compartment and the compartment also having outside communication, and two doors hinged to the edges of the end walls of the housing, said doors closing the front of said range, whereby air for the coal pot passes through said compartment. **50**

AMBROSE R. PIERCE.
